UNITED STATES PATENT OFFICE.

ALEXANDER THEODOR SARFERT, OF CHEMNITZ, GERMANY, ASSIGNOR TO DAVID GEESNER, OF WORCESTER, MASSACHUSETTS.

CLOTH-STEAMING MACHINE.

SPECIFICATION forming part of Letters Patent No. 707,725, dated August 26, 1902.

Application filed April 20, 1900. Serial No. 13,577. (No model.)

To all whom it may concern:

Be it known that I, ALEXANDER THEODOR SARFERT, a subject of the King of Saxony, and a resident of Chemnitz, Saxony, German Empire, have invented certain new and useful Improvements in Cloth-Steaming Machines, of which the following is a specification.

This invention relates to improvements in that class of machines shown and described in my application for Letters Patent filed January 20, 1898, Serial No. 667,336, said improvements including some shown but not claimed in said application, Serial No. 667,336, and others which are for the first time shown in the present application.

In my Patent No. 516,945 I showed two forms of steaming-cylinder, each of which presented the broadly novel combination, with the perforated shell and steaming-steam supply, of a heater or heat-radiator within said shell to obviate the presence in the steaming-steam of water of condensation. In both of said forms of steaming-cylinder, however, the means for handling the steam within the cylinder were simple passages devoid of steam-chambers. For this reason and also because of their relationship said passages were lacking in the efficiency attainable by the use of the improvements which are the subject of the present application.

Certain features of the invention which is the subject of the present application consist in the employment of a steam chamber or chambers interposed in the passage of the steam through the cylinder.

Other features consist in the arrangement or location or size of such steam-chambers.

Other features consist of the extension of such steam-chambers into the head or heads of the cylinder.

Other features consist in the arrangement of the steam-passages for introducing the steaming and heating steam into the cylinder and for handling the same within the cylinder, so as to efficiently apply the heat to the steaming-steam to prevent formation of water of condensation.

Other features consist in the arrangement of the steam-passages so as to more efficiently separate the water of condensation from the

steaming-steam and submit it to heat after such separation.

Other features consist in so constructing the body or core as to enable it to constitute substantially the whole heater of the cylinder, and thus enable the steam-coil of my Patent No. 516,945 to be dispensed with, if desired.

Other features, not only of the cylinder itself, but of the combination in which it is placed, will be evident from the following description.

In the accompanying drawings, Figure 1 represents a vertical longitudinal section, broken away adjacent to the middle, of a steam-cylinder such as I prefer to employ in my machine. Fig. 2 is a cross-section of the same on the line *a b* of Fig. 1. Fig. 3 is a cross-section of the cylinder on the line *c d* of Fig. 1. Fig. 4 is a top view of the steaming-cylinder, partially broken away to show the parts contained. Fig. 5 is an elevation of the side of the machine containing the driving-gears of the cylinders. Fig. 6 is a front view of said driving-gears. Fig. 7 is a plan view of said driving-gears with the upper part of the frames broken away. Fig. 8 is an elevation of the opposite end of the machine, showing the pressure-actuating mechanism. Fig. 9 is a vertical section showing said pressure-actuating mechanism. Fig. 10 is a sectional plan view of said pressure-actuating mechanism.

1 is the frame of the machine, each end of which contains a cross-piece 2, upon which is mounted a support 3, leaving an opening 5 to be occupied by parts connected with the drum.

4 and 6 are bearings supporting two steam-cylinders 7 and 8, each of which cylinders is constructed as shown in Figs. 1, 2, 3, and 4.

9 is a hollow steam-heated pressing-drum, the bearings for which, 9^a, are mounted in the forks of hangers 11 and rest on the frames 2. One of these hangers 11 is suspended at each end of the machine from the shaft 12, journaled in the supports 3. Both of the hangers 11 are keyed to said shaft, so that they are obliged to swing in unison. The journals of the steaming-cylinders 7 and 8 and drum 9

are arranged in substantially the same horizontal plane. Steam may be supplied to the interior of the drum 9 through one of its journals.

- 5 The drum 9 is moved either toward the cylinder 7 or toward the cylinder 8 for producing pressure by the following mechanism: Upon the lower ends of the hangers 11 are fixed curved racks 13, the curvature of which 10 is concentric with the shaft 12. The pinions 14 14, Figs. 6, 8, and 9, gear with said racks, respectively, and are fixed on the shaft 15, which shaft is driven by a spur-wheel 16, Figs. 9 and 10, gearing with the pinions 17 and 18, 15 which are free to revolve on the shafts 19 and 20. Duplicate mechanisms are employed for driving the shafts 19 and 20 in opposite directions as follows, a description of one being sufficient for a description of both:
- 20 21, Fig. 10, is a clutch member fixed to the pinion 18.
- 22 is a coöperating clutch member fixed to the shaft 20 and adapted to be shifted into and out of engagement with the clutch member 21 by the lever 23.
- 24 is a reel fixed to the shaft 20, upon which is coiled a rope 25, to the opposite end of which is suspended a weight in such manner that these weights tend to turn the shafts 30 19 and 20 in the directions indicated by the arrows 26 and 27 in Fig. 8.
- 28 is a ratchet-wheel fixed to the shaft 20 and which coöperates with a dog upon the under side of lever 30 to prevent the weight 35 from turning the shaft, excepting when the attendant raises said lever 30. 31 is a sprocket-wheel fixed to said shaft 20 and connected by the sprocket-chain 32 with a sprocket-wheel 33, which is turned by the hand-crank 40 34, detachably connected with said sprocket-wheel 33 by the pin 35. The clutch-levers 23 and 23^a, by which the clutches on the shafts 20 and 19, respectively, are shifted, are connected together as substantially one lever 45 and pivoted in the middle at 29, so that the opening of one clutch necessitates the closing of the other. Each of the weights constitutes in substance a pressure-motor, which motors the attendant winds up whenever required 50 by turning the cranks 34. The attendant may apply the power of either of these motors to the production of pressure by moving the lever 23 23^a so as to throw the proper clutch into engagement, then lifting one of 55 the levers 30 so as to disengage it from the ratchet 28, whereupon the descent of the weight will press the drum 9 either toward the cylinder 8 or the cylinder 7, as the case may be.
- 60 Duplicate mechanisms are employed for rotating the steaming-cylinders 7 and 8, respectively, so that a description of one rotating mechanism will answer for both, as follows: To the steaming-cylinder 7 is fixed a spur-wheel 36, Figs. 5 and 6, gearing with a pinion 37, fixed to the shaft 38. Loose on said shaft is a spur-wheel 39, carrying a clutch

member 40, Figs. 6 and 7, engaging with another clutch member 41, splined to the shaft 38 and shifted by the hand-lever 42. The 70 spur-wheel 39 gears with the pinion 43, fast on the shaft 44, which shaft carries the fast and loose driving-pulleys 45 and 46 of the machine. The two shifting-levers 42 and 42^a are fixed to the shafts 47 and 47^a, which are 75 geared together by the gears 48 and 48^a, so that the shifting of either clutch into engagement necessitates the shifting of the other out of engagement. The power from the shaft 44 is transmitted to the spur-wheel 39^a through 80 an additional pinion 43^a, so as to cause the corresponding spur-wheels 39 and 39^a of the two cylinder-rotating mechanisms to rotate in the proper relative directions for producing the alternate rotation of the steaming-cylinders 7 and 8 in the directions indicated by the arrows 49 and 50 of Fig. 5. It will thus be seen that when the attendant shifts the levers 42 42^a in one direction the cylinder 7 will be forced to rotate in the direction of 90 the arrow 49, while the cylinder 8 will be free to rotate in a direction opposite to the arrow 50, and, vice versa, when the attendant shifts the levers 42 42^a in the opposite direction the cylinder 8 will be forced to rotate in the direction of the arrow 50, and the cylinder 7 will be free to rotate in a direction opposite to the arrow 49.

51 and 51^a are beams upon which separate pieces of cloth may be rolled. Each of these 100 beams is connected with the cylinder-rotating mechanism as follows:

52, Fig. 6, is a stock in which one end of the beam 51 is fixed and which stock is fixed to a shaft 53, upon which the sprocket-wheel 105 54 is held between the friction-disks 57 and 58. A chain 55 drives the sprocket-wheel 54 from the sprocket-wheel 56, fixed to the shaft 38. Thus each cloth-beam is so operatively connected with that steaming-cylinder which 110 operates upon its cloth that the cloth-beam is driven in the opposite direction to that in which the steaming-cylinder moves, and thus the cloth as it is unwound from its steaming-cylinder is wound upon its beam, and vice 115 versa. The size of the connecting-gears of the sprockets is such that the surface speeds of the steamer and beam are approximately equal; but to provide against inequalities due to the spiral winding of the cloth I place the 120 sprocket-wheel 54 upon the shaft 53 between two friction-disks 57 and 58, which are pressed together by the thumb-screw 59, acting through the spring 60.

61 is an apron of steam-pervious material, 125 one end of which is secured to the steaming-cylinder 7 and the other end to the steaming-cylinder 8. Between said cylinders this apron passes over the heated drum 9, the heated surface of which acts to dry the apron. This 130 apron is of such length that when it is wound with a piece of cloth on either of the cylinders it is long enough to form several laps between the cloth and the perforated surface of

the cylinder and then extend spirally the length of the cloth around the cylinder and then extend over the drum 9 to and around the opposite steaming-cylinder. It is not necessary that the pressing-drum 9 be heated in all cases, as on certain goods the apron can be used to advantage by leaving in it the natural dampness resulting from the steaming it gets on cylinders 7 and 8. It is not necessary in that case that drum 9 shall be made of metal. It can be made of wood or other cheap material.

I will next describe the construction of steaming-cylinder that I prefer to employ and which is shown in detail in Figs. 1, 2, 3, and 4. It contains a perforated shell 70 and inside of the same a steam-discharger 71, a heat-radiator 72, and a water-of-condensation shield 96. The perforated cylindrical shell 70 is held at each end between the collars 74 and 75. The collars 75 fit onto the ends of the casting 72, which constitutes the body of the cylinder and which is cylindrical in form, with internal steam-chambers 77 and 77^a open at both ends at the axis of the casting and preferably with external radially-extending flanges 76. 78 is a web or diaphragm cast between the steam-chambers 77 77^a at any desired position therein, in which are placed the steam-chamber 79 and the transverse passages 71 71 for the steaming-steam, flanked by the longitudinal passages 77^b 77^b. Although I have shown the heat-radiating members 76 as integral with the body 72 and the heating-steam as passing direct from the chamber 77 to the chamber 77^a of the body 72 through the passages 77^b in the cross-diaphragm 78, it is evident that this construction may be varied in its details without essentially changing the character of the device or the principles involved. 80 and 81 are caps cast in the form shown and provided with the central passages 82 and 83, which respectively register with the openings at the opposite ends of the steam-chamber 77. The stationary pipe 84 leads from the steam-supply pipe 85 into the passage 82, and a pipe 86 leads from the chamber 77^a through the passage 83 to an escape-pipe 87. The mouth of said pipe 86 is located near the bottom of the chamber 77^a, so as to remove the water of condensation from said chamber. 88 is a stuffing-box between the stationary pipe 84 and the rotating cap 80, and 89 is a stuffing-box between the stationary pipe 86 and the rotating cap 81. Steam under high tension enters the steam-chamber 77 77^a through the pipes 85 and 84 and escapes from said steam-chamber through the pipes 86 and 87, so as to maintain the radiator-casting 72 at a high temperature. 90 is a pipe rotating with the radiator-casting and which extends from the steam-supply pipe 91, concentric with the axis of rotation, to the passage 79, being fixed to the web 78. 92 is a stuffing-box through which the pipe 90 passes, and 93 is a stuffing-box through which the pipe 91 passes. Steam under lower tension than

that supplied to the steam-chamber 77 passes from the pipe 91 through the pipe 90 and the passages 79 and 71 and is discharged from the 70 passages 79 and 71 into one of the annular spaces 94 between the flanges of the radiator, from which it passes into the spaces successively between the other flanges through the grooves 95 in the peripheries of the flanges, so 75 as to fill all the space inside of the cylindrical water-shield 96. While in this space this steam is held closely in contact with the surfaces of the radiator, which are maintained at a relatively high temperature by reason of the relatively high tension of the steam contained within the steam-chamber 77 of the radiator. Into some of the grooves 95 in the peripheries of the radiator-flanges fit corresponding depressions in the shield 96, as shown in Figs. 2 85 and 3. In the spaces made by these depressions are placed the longitudinal pipes 98 98^a and 99 99^a, the ends of which are turned inwardly at 100 toward the center of the cylinder and project through the shield 96 into the space 90 occupied by the steam next the radiator. The pipes 98 98^a and 99 99^a are perforated at 101 from end to end. The steam discharged from the passages 71 after passing in succession through the spaces 94 enters the mouths 100 95 of the pipes 98 98^a and 99 99^a and is discharged from these pipes through the perforations 101, Fig. 4. It then further distributes itself through the annular space 102 and finally escapes through the perforations in the shell 70 100 and through the apron surrounding the same into and through the successive laps of cloth and apron wound upon the cylinder. The bent mouths 100 of the pipe 98 98^a and 99 99^a project sufficiently inside of the water-shield 105 96 to take the steam from a position in the space 94 close to the radiator-surface, and therefore they take the driest portion of said steam, leaving any water of condensation trapped by said water-shield 96, where it is 110 subjected to a heat from the radiator, which in the continued use of the machine will re-convert it into steam. By the construction of the cylinder described it will be observed that the steam which is emitted from the perforated shell in passing through the cylinder is 115 so conducted and held with respect to the radiator and the water-shield as to be thoroughly dried and free from water of condensation.

In the construction above described, and shown in Figs. 1 and 2, it will be observed that the radiator and water-shield and steam-distributors 98 98^a and 99 99^a are fixed to and rotate with the perforated shell 70. The steam-supply pipes 85 and 91 by the use of a 125 reducing-valve on one may draw their supply from a common main.

106 and 107 are valves by which the supply of steam to the pipes 85 and 91, respectively, is controlled.

130 The idea of employing a steam-chamber (as, for example, in the course of the heating-steam through the cylinder) enables me by devising efficient form, size, and location

thereof to regulate the amount and distribution of the heat within the cylinder to the extent desired. In the form shown in the accompanying drawings the steam-chamber 5 77 77^a, which may be regarded either as a single or as a duplex chamber, extends at 82 and 83 into the heads or caps of the cylinder, so as to heat the same and prevent them from withdrawing the heat from the spaces within 10 the cylinder occupied by the steaming-steam. Said steam-chamber 77 77^a is also shown as of a diameter at least one-third ($\frac{1}{3}$) the internal diameter of the shell, and if made of these proportions it is capable of containing 15 a sufficient body of steam to supply the necessary heat for the entire space within the shell, so as to enable the constructor to dispense, if desired, with the steam-coil shown in my said Patent No. 516,945. The external diameter 20 of the body or core 72 if made, as shown in the drawings, more than two-thirds ($\frac{2}{3}$) the internal diameter of the shell will conduct the heat from the body of steam within the steam-chamber 77 77^a into close proximity to 25 the interior of the shell, and thus maintain the requisite temperature in the annular film of steaming-steam passing to the perforations of the shell. Since according to the proportions shown in the drawings for a cylinder one 30 foot in external diameter the annular space between the exterior of the core or body and the interior of the shell will be only about one inch in thickness, the longitudinal steaming-steam passages 98, 98^a, 99, 99^a, and 95 are 35 accommodated without increasing the thickness of said annular space by placing said longitudinal passages, as shown, in depressions in the surface of said body or core. The dimensions above referred to are at. 40 tained, as shown in the drawings, without necessitating the enlargement of the journals of the cylinder, which are shown as less in diameter than the core or body 72 or even than the steam-chamber 77 77^a. Not only 45 does the idea of employing a steam-chamber within the shell enable the constructor to efficiently maintain the temperature of the steaming-steam while it is passing in the annular space between the core and the shell, 50 as above described, but it also enables the constructor to efficiently maintain the temperature of the steaming-steam on its way through the cylinder to said space. Thus, as shown in the drawings, the steaming-steam 55 from its point of entrance into said cylinder may be led along a chambered portion of said core, (preferably through one of the chambers itself,) so as to subject the steaming-steam to the heat of said chamber. Moreover, the 60 employment of the steam-chamber 79 enables the steaming-steam to be temporarily held, if desired, in a position wherein it is subject to the heat from both the chambers 77 and 77^a, after which it is trapped by the inwardly-projecting nozzles 100 while still held in contact with the core within the passages 94, which act as a preliminary-expansion chamber for

the steaming-steam preparatory to its final expansion after it passes out of the pipes 98 98^a and 99 and 99^a. At the point in the chamber 79 where the distribution of the steaming-steam begins it is thoroughly subject to the heat of the adjacent steam-chambers. When the distribution commences, therefore, the heating-steam is not only thus fortified against 75 the formation of water of condensation, but it starts from substantially the middle of the cylinder, so as to insure a substantially equal distribution of temperature of the steam emitted at different parts of the perforated 80 shell. The steam thus starting under the best conditions is first divided into two parts by the two discharge-passages 71 71, which deliver it from opposite sides of the core into the passage 94. Here each half of the steam 85 is again divided into substantially two parts, which flow, respectively, toward the opposite ends of the cylinder, each part being subject to substantially the same conditions and each part being again subdivided by the perforated pipes 98 98^a 99 99^a. 90

Although I have above described with minuteness of detail the various features of the construction shown in the accompanying drawings, I am well aware that many of these 95 details may be omitted without departing from my invention, and I therefore do not wish my description to be taken as indicating an intention to limit myself to the same.

Although I have shown the journals, heater, 100 and steam-passages as rotating with the perforated shell instead of being stationary, I do not wish to limit this patent to this feature.

I claim—

1. In a cloth-steaming cylinder, containing 105 a perforated shell, the combination within said shell, of a steam-discharger, a radiator, a water-shield surrounding the same and a perforated distributor whereby the steam from within said water-shield is distributed 110 outside of the same, substantially as described.

2. In a cloth-steaming cylinder, in combination, a perforated shell, a steam-chambered radiator-casting upon which said shell is 115 mounted and means whereby the steam for steaming is conducted through said casting, and means whereby said steam is confined in contact with the outer surface of said casting, substantially as described. 120

3. In a cloth-steaming machine, in combination, two steaming-cylinders, means for driving the same, a steam-pervious apron having its opposite ends secured to said steaming-cylinders, a presser intermediate said cylinders and mechanism whereby said presser may be moved toward either cylinder, substantially as described. 125

4. In a cloth-steaming machine, in combination a steaming-cylinder, an apron having one end secured on said steaming-cylinder, a cylinder on which the opposite end of said apron is secured, a presser in contact with which said apron travels between said cyl- 130 in-

- ders and means whereby said presser is moved to or from said steaming-cylinder, substantially as described.
5. In a cloth-steaming cylinder, in combination, a perforated shell 70, a chambered body 72 containing a laterally-extending passage 71, a pipe 90 conveying the steaming-steam through a journal of the cylinder to said passage 71, a water-shield in the path of 10 the steaming-steam between said passage 71 and the perforations of the shell and a pipe for conveying the heating-steam into said body, substantially as described.
6. In a cloth-steaming cylinder, in combination, a perforated shell 70, a chambered body 72 containing a laterally-extending passage 71, a pipe 90 conveying the steaming-steam through a journal of the cylinder to said passage 71, a water-shield in the path of 15 the steaming-steam between said passage 71 and the perforations of the shell and a pipe for conveying the heating-steam into said body and heat-radiating members in the path of the steaming-steam between said passage 20 71 and the perforations of the shell, substantially as described.
7. In a cloth-steaming cylinder, in combination, a perforated shell 70, a body containing the chambers 77 and 77^a, respectively, at 25 opposite ends thereof, means for supplying heating-steam to said chamber 77, a steam-passage from said chamber 77 to said chamber 77^a, an exit for the heating-steam from said chamber 77^a, a laterally-extending passage 71 located between said chambers and a pipe 90 for supplying the steaming-steam to said passage 71, substantially as described.
8. In a cloth-steaming machine, the combination of two steaming-cylinders adapted to 30 receive the cloth thereon, and a pressing-cylinder, with swinging cylinder-supports whereby the pressing and steaming cylinders may have relative movement toward and from each other, substantially as described.
- 45 9. In a cloth-steaming machine, the combination of two steaming-cylinders adapted to receive the cloth thereon, and a pressing-cylinder, with swinging cylinder-supports whereby the pressing and steaming cylinders may 35 have relative movement toward and from each other and a yielding power connection to said swinging supports, substantially as described.
- 50 10. In a cloth-steaming machine, the combination of two rotatable steaming-cylinders, a steam-pervious apron connected to both cylinders to be alternately wound thereon together with a piece of cloth, with a pressing-cylinder intermediate the steaming-cylinders, swinging supports for the journals thereof, and means for applying power to 40 said pressing-cylinder to swing it toward either steaming-cylinder, substantially as described.
- 55 11. In a cloth-steaming machine, the combination of plural steaming-cylinders adapted 45 to receive the cloth thereon, with a pressing-cylinder adapted to engage the cloth as wound upon each steaming-cylinder, guides for the journals of the pressing-cylinder, and means 50 for moving said journals in said guides toward and from the steaming-cylinders, substantially as described.
12. In a cloth-steaming machine, the combination of two steaming-cylinders adapted 55 to receive the cloth thereon, with a pressing-cylinder between the steaming-cylinders, guides for the journals of the pressing-cylinder adapted to permit the engagement of said cylinder with either steaming-cylinder and a 60 power connection with said pressing-cylinder to move it in said guides, substantially as described.
13. In a cloth-steaming machine, the combination of two steaming-cylinders adapted 65 to receive the cloth thereon, with a pressing-cylinder between the steaming-cylinders, guides for the journals of the pressing-cylinder adapted to permit the engagement of said cylinder with either steaming-cylinder, swing- 70 ing yokes embracing the journals of the pressing-cylinder and extending transversely of said guides and means for swinging said yokes, substantially as described.
14. In a cloth-steaming machine, the combination of two steaming-cylinders adapted 75 to receive the cloth thereon, with a pressing-cylinder between the steaming-cylinders, guides for the journals of the pressing-cylinder adapted to permit the engagement of said cylinder with either steaming-cylinder, swing- 80 ing yokes embracing the journals of the pressing-cylinder and extending transversely of said guides, a segment-gear upon each 85 yoke, gears engaging said segments and rotative power connections to said gears, substantially as described.
15. In a cloth-steaming cylinder, in combination, a perforated shell, a steam-chamber, an induction-passage into said steam-chamber, an eduction-passage from said steam-chamber, a steaming-steam passage leading to substantially the center of said cylinder and steaming-steam passages extending from the center to the periphery.
16. In a cloth-steaming cylinder, in combination, a perforated shell, two steam-chambers within the same, induction-passages to both of said chambers, an eduction-passage from one of said chambers discharging the 100 steaming-steam within said shell and an eduction-passage from the other of said chambers discharging outside of said shell.
17. In a cloth-steaming cylinder, in combination, a perforated shell, a core provided 105 with two longitudinal and induction steam-passages, a steam-chamber, a lateral passage connecting with said chamber.
18. In a cloth-steaming cylinder, in combination, a perforated shell, end journals, a 110 core of greater diameter than said journals provided with a steam-chamber, means for

supplying said chamber with steam and separate means for supplying said perforations with steam.

19. In a cloth-steaming cylinder, in combination, a perforated shell, end journals, a core having a steam-chamber of greater diameter than said journals, means for supplying said steam-chamber with steam and separate means for supplying said perforations with steam.

20. In a cloth-steaming cylinder, in combination, a perforated shell, means for supplying said perforations with steam and a core having a steam-chamber; the external diameter of said core exceeding two-thirds of the internal diameter of said shell whereby the requisite temperature of the steaming-steam may be maintained by the heat from said core until it reaches the perforations of said shell.

21. In a cloth-steaming cylinder, in combination, a perforated shell, means for supplying steam to said perforations and a core having a steam-chamber, the diameter of said steam-chamber exceeding one-third the internal diameter of said shell whereby a sufficient body of steam is maintained in said chamber to maintain the space within the shell at the requisite temperature for the steaming-steam.

22. In a cloth-steaming cylinder, in combination, a perforated shell, a core containing a steam-chamber, means for supplying heating-steam thereto and a steaming-steam passage extending along the chambered portion of said core.

23. In a cloth-steaming cylinder, in combination, a perforated shell, a core containing a steam-chamber extending substantially to both ends and a steaming-steam passage extending along a chambered portion of said core.

24. In a cloth-steaming cylinder, in combination, a perforated shell, a core provided with a steam-chamber, means for supplying heating-steam to said chamber and a steaming-steam passage extending through said chamber.

25. In a cloth-steaming cylinder, in combination, a perforated shell, a core provided with a steam-chamber, means for supplying heating-steam to said chamber, a steaming-steam passage extending through said core along a chambered portion thereof and thence out to the periphery thereof.

26. In a cloth-steaming cylinder, in combination, a perforated shell, a core provided with a steam-chamber, means for supplying heating-steam to said chamber and separate means for supplying steaming-steam to the interior of said shell.

27. In a cloth-steaming cylinder, in combination, a perforated shell provided with a steam-chamber near each end, a heating-steam-supply passage leading into one of said chambers, a water-of-condensation passage leading from the other of said chambers, a steam-passage connecting the two chambers

and means for supplying steaming-steam to the interior of said shell.

28. In a cloth-steaming cylinder, in combination, a perforated shell, a core containing adjoining induction-passages for the steaming-steam and heating-steam, respectively, a passage by which said heating-steam is conducted around said steaming-steam after leaving said induction-passage.

29. In a cloth-steaming cylinder, in combination, a perforated shell, a steaming-steam chamber located a substantial distance within the end of the cylinder, a passage whereby heating-steam is conducted outside of and in contact with the walls of said chamber and means whereby said chamber is supplied with steaming-steam.

30. In a cloth-steaming cylinder in combination, a perforated shell, a core or drum therein containing separate chambers for the reception of the heating-steam and the steaming-steam, said chambers being designed for the transfer of heat from the heating-steam to the steaming-steam.

31. In a cloth-steaming cylinder, in combination, a perforated shell, a steam-chambered heater within the same provided with a longitudinal depression in its exterior surface and a steaming-steam passage in said depression.

32. In a cloth-steaming cylinder, in combination, a perforated shell, a steam-chambered heater within the same, a steaming-steam-distributing pipe between it and said perforated shell, a nozzle projecting from said pipe nearer the center than parts of greatest diameter of said heater whereby the water is trapped substantially within the field of said heater and an induction steaming-steam-supply pipe.

33. A cloth-steaming-cylinder core containing, in combination, the heating-steam chambers 77 and 77^a adjacent to opposite ends, a passage 77^b connecting the same, a laterally-extending steaming-steam passage intermediate said end chambers and an induction-passage to said lateral passage.

34. A cloth-steaming-cylinder core containing, in combination, the heating-steam chambers 77 and 77^a adjacent to opposite ends, a laterally-extending steaming-steam passage intermediate said end chambers and an induction-passage to said lateral passage.

35. A cloth-steaming-cylinder core containing, in combination, the heating-steam chambers 77 and 77^a adjacent to opposite ends, a laterally-extending steaming-steam passage intermediate said end chambers and an induction-passage to said lateral passage; said induction-passage passing through one of said end chambers.

36. A cloth-steaming-cylinder core containing, in combination, the end heating-steam chambers 77, 77^a, a steaming-steam chamber 79 intermediate the same, a passage from said chamber 79 to the periphery and an induction-passage to said chamber 79.

37. A cloth-steaming-cylinder core, containing in combination, the end heating-steam chambers 77 and 77^a, an intermediate laterally-extending steaming-steam passage, a 5 steaming-steam induction-passage and means whereby water is trapped in passing laterally outward from said induction-passage.

38. In a cloth-steaming cylinder, in combination, a perforated exterior shell, a core containing the end heating-steam chambers 77 and 77^a and a laterally-extending steaming-steam passage intermediate the same, an induction-passage to said intermediate passage and a trap for holding back the water of con- 15 densation as the heating-steam passes from said induction-passage to said perforated shell.

39. In a cloth-steaming cylinder, in combination, a perforated exterior shell, a rotating 20 core carrying the same and provided with journals and with the end heating-steam chambers 77 and 77^a and with an intermediate laterally-extending steaming-steam passage, induction heating-steam and steaming-steam 25 passages through one of said journals and an eduction-passage from said heating-steam chamber through the other of said journals.

40. In a cloth-steaming cylinder, the combination with an outer perforated cylinder, of 30 an inner heating-core having therein distinct chambers for the reception of the heating and the steaming steam, means for discharging the steaming-steam from its chamber into the perforated cylinder and means for separately 35 supplying each chamber with its steam.

41. In a cloth-steaming cylinder, the combination with an outer perforated cylinder, of an inner heated core having therein distinct

chambers for the reception, respectively, of the heating and steaming steam, means provided with a water-trap for discharging the steaming-steam from its chamber into the perforated cylinder and means for supplying each chamber with its steam. 40

42. In a cloth-steaming cylinder, in combination, a perforated shell, a heating-core containing a heating-steam chamber and a laterally-extending steaming-steam passage, an induction-passage to said lateral passage and a longitudinally-extending perforated distrib- 45 50 eter whereby the steam is distributed outside of said core.

43. In a cloth-steaming cylinder, in combination, a perforated shell, a heating-core containing a steaming-steam chamber and a lat- 55 erally-extending steaming-steam passage, an induction-passage to said lateral passage, a longitudinally-extending distributor between said core and said perforated cylinder and means whereby the water is trapped as said 60 steam passes from said induction-passage to said longitudinal distributor.

44. In a cloth-steaming cylinder, in combination, a perforated shell, a heating-core containing a heating-steam chamber, means 65 whereby the steaming-steam is conducted through said core and means whereby said steaming-steam is caused to flow against the surface of said heating-core.

In testimony whereof I have signed my 70 name in the presence of two subscribing witnesses.

ALEXANDER THEODOR SARFERT.
